UNITED STATES PATENT OFFICE.

JOHN W. McCLEAN, OF SPOKANE, WASHINGTON.

BERRY BOX.

Application filed May 8, 1923. Serial No. 637,484.

To all whom it may concern:

Be it known that I, JOHN W. McCLEAN, a citizen of the United States, residing at Spokane, in Spokane County and State of Washington, have invented certain new and useful Improvements in Berry Boxes, of which the following is a specification.

My present invention relates to improvements in berry boxes of the folded-blank type, wherein a single, integral blank is cut, as by means of a die, to special shape, and the cut blank is adapted for use by folding or bending to form its sides and bottom. The bottom is fashioned with overlapping sections securely locked together to provide a reinforced and rigid bottom for the open top box, and a single side flap is utilized for locking the box or tray in position for use.

The primary object of the invention is the provision of a light but strong box to be used as a container and for shipping purposes in connection with berries and similar commodities which box is comparatively inexpensive in cost production, well braced, and durable, and preferably made up of cardboard.

The box blanks as cut to shape, before folding, may be compactly piled and secured for shipment, and the blanks may with facility and convenience be bent and folded into boxes or containers either for sale-display or for shipping purposes.

In the accompanying drawings I have illustrated one complete example of the physical embodiment of my invention wherein the parts are combined and arranged according to one mode I have so far devised for the practical application of the principles of my invention for the production of a rectangular shaped box or tray.

Figure 1 is a perspective view of a berry box embodying my invention.

Figure 2 is a view in perspective of the box blank, partly folded, and illustrating the process of forming the box.

Figure 3 is a perspective view showing the bottom of the completed box.

Figure 4 is a plan view of the cut box-blank, before folding or bending.

The box as illustrated is preferably of rectangular shape with open top, and the material used may be card-board, fiber or similar material adapted for the purpose. It will be understood that other forms or shapes of the box are contemplated, but for

convenience of illustration and description, a rectangular box is hereinafter referred to.

The four sides 1, 2, 3, 4, of similar size and shape, form integral parts or sections of the single-piece blank, which is scored on its longitudinal axis and along its median line A (as indicated by a light line) in order that the four sections 5, 6, 7, 8, may be folded or bent to form the bottom of the box. The four bottom sections are substantially of the same size and shape, and are designed for co-action to form a reinforced bottom member for the box when completed.

The blank is scored transversely at three equidistant points as indicated by the light line B upon which the bends or folds are made for forming the respective sides of the rectangular box. These three light lines indicating scoring are continued by heavy lines C (which indicate cuts or slits through the material of the blank) across the portion of the blank from which the bottom sections are formed, in order that the sections 5, 6, 7, 8, may be folded to form the bottom of the box.

For supporting the completed box in upright position and slightly elevated from its support I utilize corner feet which are fashioned by cutting out three tabs 9 which are located on the axis lines B-C of the blank between the ends of the blank. These tabs are each bounded by a heavy line in Figure 4 to indicate that the tab is cut or stamped from the material by a tool having three cutting edges as indicated, and the tab is adapted to be folded on the line B to form an angular foot.

At the respective ends of the blank a fourth foot is provided for by cutting out two complementary tab sections 10 and 11. The tab 11 it will be observed is a half-section, while the tab 10, which is to be bent along the transverse edge of the blank, is a full tab and is adapted to be folded around the half-section 11 to form the completed foot.

The adjoining bottom sections 5, 6, 7, 8, of the box are designed to overlap and form a horizontal bottom member, and these overlapping sections are interlocked through the instrumentality of slits 12 cut diagonally in the sections extending from the bending line A for a suitable distance through the body of the sections, and located in the same relative positions. These cuts or slits are

designed to receive respective corners 13 of the four bottom sections, after the sections have been bent along the line A.

At the long free edge of each bottom section an angular notch 14 is cut therefrom, said notch being located equidistant between the short ends of the sections, in order that the overlapping bottom sections may be interlocked, and their joint at the center of the box bottom be freely made with a comparatively smooth upper surface for the box bottom, as shown.

At the respective ends of the blank, co-acting means are provided for locking the folded members of the box together. These means include a slit 15, cut by a tool having the necessary three cutting edges, and disposed at or near the end of the box-side 4, and also a locking flap 16 at the opposite end of the box blank, which flap forms a continuation of the box side 1. The blank is scored on the line 17 in order that the flap 16 and the foot-tab 10 may be bent at right angles to the side 1, and to permit the flap 16 to be bent around the box side 4 in completing the box. This flap is notched at 18 to form a locking head 19 which may be inserted in the slot or slit 15 of the box side 4.

The box may be fashioned from the blank in any convenient manner as for instance by first bending the blank on the lines B (the slits C permitting freedom of movement) and bending the locking flap 16 and foot 10 on line 17. Then the bottom sections are folded at right angles to the side sections leaving the feet rigid with the sides of the box, and the opposite ends of the sectional box side are brought together as indicated in the initial movement in Figure 2.

In Figure 2 it will be seen that the bottom sections, as they are brought together, are made to overlap, with the respective cor-

ners 13 beneath an adjoining section. As the box members are closed in these corners 45 are inserted in the complementary slits 12, as seen at the right in Figure 2, and when all of the corners have been inserted in their slits, a continued closing movement of the bottom sections will cause each section to 50 be locked in its adjoining section, as seen in Figures 1 and 3. After the bottom sections are in place the flap 16 is turned around and laid flat against the side 4, and head 19 is slipped into the slit 15 to lock 55 the box by a single element. The slit it will be observed is disposed horizontally in the side 4 and the head is slipped therein in a vertical plane, thus bringing any strains or pull of the flap on the head 19. The head 60 through the notch 18 is prevented from being dislodged for the reason that a lateral strain is absorbed between the head and the left end or wall of the slit 15.

In this manner a comparatively light, 65 durable, and neat appearing box is provided, which is braced and strengthened by the interlocking bottom sections, and the parts are securely locked in normal position.

Having thus fully described my invention, what I claim as new and desire to secure by Letters Patent is;

A box made from a single folded blank having sides and overlapping bottom sections of uniform size and shape, said sections having complementary edge notches forming a center opening in the box bottom, co-acting means for interlocking adjoining bottom sections, said sides having rigid extensions cut out of the bottom sections and forming angular feet at the corners of the box, a slit in one side, a folded flap on an adjoining side, and a notched head on said flap to engage said slit.

In testimony whereof I affix my signature.
JOHN W. McCLEAN.
